HAT FLANGING AND HYDRAULIC MACHINE

Morris Schildhaus, New York, N. Y.

Application April 1, 1937, Serial No. 134,244

5 Claims. (Cl. 223—13)

This invention relates to new and useful improvements in a hat flanging and hydraulic machine to produce a mellow hat. The body may be made solid (compact) by pressing the pores together. The invention makes use of rubber parts for contacting the hat during the application of the pressure to obtain the mellow quality.

Furthermore it is proposed to save one operation by treating the brim and crown simultaneously. The hat brim need not be curled, therefore the edge will not be cracked.

The invention has for an object the construction of a machine as mentioned which is adapted to give a better flanged hat, to give a brim as mellow or firm as desired, and to give uniform pressure on the entire surface of the brim for uniformly shaping and finishing it.

More specifically, the invention proposes the construction of a machine as mentioned which is characterized by a hat block top section mounted on a pressure carriage and cooperative with a bottom section, and comprising a hollow body for hydraulic substance, and a conformable diaphragm in the bottom of said hollow body and engageable on the flange or brim of a hat on a block bottom section, for transferring pressure thereto.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary perspective view of a machine constructed according to this invention.

Fig. 2 is a fragmentary sectional view taken on the line 2—2 of Fig. 1.

Fig. 3 is a fragmentary front elevational view of the machine.

Fig. 4 is a fragmentary sectional view taken on the line 4—4 of Fig. 2.

Fig. 5 is a horizontal sectional view taken on the line 5—5 of Fig. 3.

Fig. 6 is a sectional view taken on the line 6—6 of Fig. 3.

Fig. 7 is a fragmentary sectional view similar to Fig. 4 but illustrating a modification of the invention.

Fig. 8 is a fragmentary sectional view taken on the line 8—8 of Fig. 7.

Fig. 9 is an elevational view looking in the direction of the line 9—9 of Fig. 8.

Fig. 10 is a sectional view taken on the line 10—10 of Fig. 7.

Fig. 11 is an enlarged detailed view of a portion of Fig. 7 showing certain of the parts separated.

Fig. 12 is a reduced elevational view looking in the direction of the line 12—12 of Fig. 11.

The hat flanging and hydraulic machine, according to this invention, comprises a frame consisting of a top member 10 supported by a pair of side members 11, to a base member 12. A transverse brace 13 is mounted between intermediate points of the side members 11. An annular hat block bottom section 14 is movably supported on said frame and is adapted to be positioned in a pressure receiving position. A pressure carriage 15 is mounted on said frame above said pressure receiving position. A hat block top section 16 is mounted upon the pressure carriage and is cooperative with the bottom section and comprises a hollow body 16^a for hydraulic substance and a conformable diaphragm 17 on the bottom of said hollow body and engageable on the flange or brim of a hat on said bottom section for transferring pressure thereto. The center of the diaphragm 17 is secured to the center of the hollow body by a bolt 16' or the like.

The pressure carriage includes a pair of sleeves 15^a which are slidably mounted on the side members 11. These sleeves are fixedly mounted upon the sides of the hollow body 16^a. At spaced positions on the body 16^a there are pairs of lugs 18 to which links 19 pivotally connect. These links 19 pivotally connect with links 20 which are pivotally supported at their top ends upon the bottom face of the frame head member 10. A lever 21 projects from one of the links 19 by which said link may be pivoted to align the links 19 and 20 and so force the pressure carriage downwards. The parts are arranged so that when these links are nearly aligned in a vertical plane the hot block sections are engaging each other. It is thus possible to manually apply a great pressure between the block sections. The carriage 15 is counter-balanced by cables 23 which extend upward over guides 24 and then extend downward over guides 24^a. The latter downward extending ends of these cables support a counter-weight 26.

The bottom block section 14 is supported upon an undercarriage 27 which has several casters 28 engaging a track 29 extended outwards to the front of the machine. The undercarriage 55

27 is provided with a handle 30 by which it may be gripped and moved outwards. The under-carriage 27 is in the form of an annular hollow body in which a heater 31 (electric or gas) is 5 mounted. Gas pipes 31^a or steam pipe 31^b may also be connected with the interior of the under-carriage by which it may be heated. This heater 31 is connected with an electric line 32 which may be connected with a source of electricity. 10 The block bottom section 14 also is of annular shape and has an inside wall 14^a into which a hat body may engage. This annular member has a curved top and side wall 14^b upon which the brim or flange of the hat may rest. 15 The block member section has an annular ring 34 which clamps down on annular canvas or other gasket 35 adjacent which the diaphragm 17 is positioned. The diaphragm 17 extends across the bottom of the hollow body 16^a and is 20 secured in position by bolts 36 which engage through a flange on the hollow body 16^a and through the annular member 34. The diaphragm 17 is conformable with the curved shape of the side 14^b of the bottom block section. 25 The hollow body 16 may be filled with hydraulic substance through a funnel 38 which is mounted on the top of the body. A valve 39 controls the discharge of hydraulic substance from the funnel 38. A pressure valve 40 is 30 mounted on the hollow body 16^a and may be connected with or shut off from the hollow body by a control valve 41.

The operation of the device is as follows:

The valve 39 is opened and the compartment 35 within the hollow body 10 is filled with a hydraulic substance. The bottom block section 14 is then drawn out by pulling on the handle 30 so that under-carriage moves outwards. A hat is then dropped into the bottom block section as indicated by the dot and dash lines 49, in Fig. 4. The bottom block section is then moved inwards to its pressure receiving position as shown in Fig. 4. Then the lever 21 is pivoted downwards to pivot the links 19 and 20 and force the back pressure downwards.

45 The diaphragm 17 will strike the flange or brim of the hat 49 and will conform with the shape of the hat. The hydraulic substance within the compartment 16^a will flow to permit the diaphragm 17 to conform with the block bottom section, and after the conformation the hydraulic substance will be incompressible so that it is possible to transfer a large pressure against the brim of the hat. The pressure may be watched by watching the gauge 40.

55 In Figs. 7-12 inclusive, another embodiment of the invention has been disclosed which is very similar to the previous form, distinguishing merely in details of the different parts. According to this form of the invention there is a machine frame which includes the side members 11'. On these side members there is a pressure carriage 15' which is slidably mounted. This pressure carriage is controlled by a pressure system which includes the links 19' and the manually operable handles or lever 21'. An annular hat block bottom section 14' is mounted on an under-carriage 27' which is slidable on tracks 29' forming a portion of the bottom member 12' of the frame of the machine.

The block top section has a hollow body 16^a across the bottom side of which there is a diaphragm 17'. This diaphragm is shaped to have a projecting central portion 17^a which is adapted to engage into the crown of the hat 49' mount-

ed on the bottom section 14' so that hydraulic pressure may also be extended to the crown of the hat as well as the brim. A hydraulic substance supply funnel 38' is connected with the hollow body 16^a. A pressure gauge 40' is mounted upon the hollow body 16^a. An air supply pipe 40^a with a control valve 40^b connects with the gauge 40' to which there is also connected an exhaust line 40^c with a control valve 40^d. A pipe 40^e connects the gauge 40' with the hollow body 16^a. The funnel 38' is controlled by a valve 39' and supplies hydraulic substance to the body 16^a. The diaphragm 17' is held in position by an annular canvas element 35' and an annular member 34'. 15

The under-carriage 29' has a large interior compartment 59 with several openings 51 in the walls thereof. Through these openings air is supplied for gas burners 31^b on the inner ends of gas pipes 31^a. The bottom block section 14' is 20 formed of two members. There is a bottom member 14^x adapted to extend completely around and encase the crown of a hat. The top member 14^y is aligned with the bottom member 14^x by notches 53 and corresponding protruding 25 members 54 on the parts which are held connected by several screws 52. Furthermore a projection 55 from the bottom member 14^x engages a recess 56 in the top member 14^y.

A sheet rubber covering member 14^c extends 30 over the outer surface of the top member 14^y and is held in position by an annular projecting rib 56^a on the covering member engaging in a groove in the side of the top member 14^y. Projections 57 from the covering member 14^c are engageable 35 in receiving recesses 58 in the bottom member for assisting in holding the members together and for holding the covering member 14^c.

In other respects this form of the invention is identical to the previous form and similar parts 40 and the operation may be readily understood by an inspection of the parts and a consideration of the prior form. The main distinguishing feature of this modified form of the invention is that the crown as well as the brim of a hat will 45 be treated with pressure.

While I have illustrated and described the preferred embodiments of my invention, it is to be understood that I do not limit myself to the precise constructions herein disclosed and the 50 right is reserved to all changes and modifications coming within the scope of the invention as defined in the appended claims.

Having thus described my invention, what I 55 claim as new, and desire to secure by United States Letters Patent is:

1. In a hat flanging machine, an annular recessed hat block bottom section adapted to be engaged by an annular hat block top section for blocking a hat when pressure is applied to the top section, said bottom block section consisting of an upper part and a lower part, means for aligning and holding said parts together, a rubber sheet covering said top part, an annular projecting rib on said rubber sheet engaging a complementary groove in said upper part for holding said rubber sheet in position thereon, and a plurality of projections on said rubber sheet adjacent the edge of said upper part which are adapted to engage complementary recesses in 60 said lower part for aligning said rubber sheet on said upper part and for assisting in holding said rubber sheet in position on said upper part.

2. In a hat flanging machine, an annular recessed hat block bottom section adapted to be en- 75

gaged by an annular hat block top section for blocking a hat when pressure is applied to the top section, said bottom block section consisting of an upper part and a lower part, means for aligning and holding said parts together, a rubber sheet covering said top part, an annular projecting rib on said rubber sheet engaging a complementary groove in said upper part for holding said rubber sheet in position thereon, and a plurality of 5 projections on said rubber sheet adjacent the edge of said upper part which are adapted to engage complementary recesses in said lower part for aligning said rubber sheet on said upper part and for assisting in holding said rubber sheet in 10 position on said upper part, said means for aligning and holding said parts together, comprising a cam on one of the parts engaging a complementary cam recess on the other of the parts for aligning said parts, and a holding means on one 15 of the parts engaging the other of the parts for holding said parts together in their aligned positions.

3. In a hat flanging machine, an annular recessed hat block bottom section adapted to be engaged by an annular hat block top section for blocking a hat when pressure is applied to the top section, said bottom block section consisting of an upper part and a lower part, means for aligning and holding said parts together, a rubber sheet covering said top part, an annular projecting rib on said rubber sheet engaging a complementary groove in said upper part for holding said rubber sheet in position thereon, and a plurality of 20 projections on said rubber sheet adjacent the edge of said upper part which are adapted to engage complementary recesses in said lower part for aligning said rubber sheet on said upper part and for assisting in holding said rubber sheet in position on said upper part, 25 said means for aligning and holding said parts together, comprising a cam on one of the parts 30

engaging a complementary cam recess on the other of the parts for aligning said parts, and a holding means on one of the parts engaging the other of the parts for holding said parts together in their aligned positions, said holding means 5 comprising screws passing through one of the parts and threadedly engaging the other of the parts.

4. In a hat flanging machine, an annular recessed hat block bottom section adapted to be engaged by an annular hat block top section for blocking a hat when pressure is applied to the top section, said bottom block section consisting of an upper part and a lower part both having a central opening and the opening in said upper 10 part being slightly larger than the opening in said lower part, a sheet of compressible substance covering said upper part and consisting of a top portion having a central opening and covering the top of said upper part, and a depending 15 flange portion continuing from the edge portion of said top portion around said central opening and extending into said upper part until its bottom edge engages the top edge of said lower part to decrease the size of the opening in said top 20 part to a circumference in which the sides of said top part will be in an aligned position with the sides of said lower part.

5. A bottom block for a hat flanging machine comprising a lower part having an inner surface 30 of comparatively hard material, and having a central opening at the top thereof, an upper part having a central opening cooperating with the opening in the lower part, said upper part having a brim-engaging portion, the top surface 35 thereof being covered with yieldable material, the inner surface of the opening in the upper part being aligned with the inner surface of the lower part.

MORRIS SCHILDHAUS. 40
